HEATER

John W. Miller, Lansing, Mich., assignor to Motor
Wheel Corporation, Lansing, Mich., a corpora-
tion of Michigan

Application February 1, 1944, Serial No. 520,620

2 Claims. (Cl. 98—33)

1

This invention relates to heaters and more particularly to a novel construction and arrangement of parts whereby to provide a forced circulation of air for space heaters of the circulating type without affecting their capacity to circulate air by gravity.

Circulating space heaters are conventionally used to heat small dwelling, trailers or other small structures where space is at a premium. One of the difficulties encountered in heating such structures is to avoid underheating the floor while overheating the ceiling. This is especially so in trailers where the floor is exposed to the outside temperature. This difficulty can be overcome, of course, if it is desired to resort to an elaborate air circulating and distributing system. However, the limitations of space and cost do not permit of that in many instances.

Accordingly, it is the principal object of this invention to provide a simple and inexpensive unit which may be conveniently installed in a small space and combined with a circulating heater to discharge heated air at the floor level. In order to do this, it will be understood that it is necessary to force the heated air to flow in a direction contrary to the natural gravity flow thereof. It has been discovered that by discharging the heated air at floor level and distributing it around the space to be heated in proper proportions, the relative difference in temperature between the floor and ceiling is reduced to a minimum.

Other objects and advantages of the invention will appear from a reading of the following specification in connection with the accompanying drawings, wherein:

Figure 1 is a front elevational view of an apparatus embodying the present invention, with a portion of the heater casing removed to show the stove and interior of the casing;

Figure 2 is a bottom plan view of the heater shown in Figure 1;

Figure 3 is a top plan view of the air circulating and distributing unit forming a part of the apparatus shown in Figure 1;

Figure 4 is a side elevational view of the unit shown in Figure 3;

Figure 5 is a front elevational view of the unit shown in Figure 3;

Figure 6 is a top plan view similar to Figure 3 but with the top wall of the unit removed;

Figure 7 is a sectional view taken on the line 7—7 of Figure 6;

Figure 8 is a sectional view taken on the line 8—8 of Figure 3; and

2

Figure 9 is a sectional view taken on the line 9—9 of Figure 3.

The apparatus shown in Figure 1 includes a circulating space heater designated generally by the reference numeral 10 and an air circulating and distributing unit designated generally by the reference numeral 25. Each of these two members is self contained and capable of use independently of each other.

10 The circulating heater 10 comprises a stove 11 which may be of any conventional type, such as the oil burning type shown in Figure 1 of the patent to Valjean No. 2,073,270. The details of the stove form no part of the present invention, so they are not here shown or described. The stove may be provided with supporting legs 12, a door 13, and an exhaust pipe 14, the latter being adapted to be connected to a chimney, not shown. Fuel may be supplied to the stove from a source not shown through a valve controlled supply pipe 15. By means of the valve, the quantity of fuel supplied to the burner and consumed therein, and therefore, the quantity of heat generated can be conveniently regulated.

25 The stove 11 is enclosed on its sides and top by a casing 16, the lower edge of the casing being at the level of the lower extremities of the stove legs 12 so as to be supported by the same support as the stove. The casing 16 is arranged in spaced relation to the stove to provide a space therebetween within which air is heated. The side walls of the casing 16 are provided with louvered air inlet openings 17 adjacent the lower extremities thereof; and the top wall is provided with a louvered outlet opening 18. Thus, the heater is capable of circulating air by gravity, the cold air being drawn in through the openings 17 and the heated air being discharged through the opening 18.

30 40 Within the casing 16 there is disposed an air duct 19 which extends from near the top of the casing to near the bottom thereof. The duct 19 is provided with an inlet opening 20 at its upper end and an outlet opening 21 at its lower end (see Figures 1 and 2). The outlet opening 21 is adapted to register with an inlet opening in the top wall of air circulating and distributing unit 25, as will be described presently.

45 50 The details of the air circulating and distributing unit 25 are shown in Figures 3 to 9 inclusive. Figures 3, 4 and 5 show the exterior of the unit which comprises a casing having a bottom wall 26, side walls 27 and 28, a front wall 29, a rear wall 30, and a top wall 31 formed to provide a

raised housing 32 to enclose a blower and motor as will be described presently.

The interior of the air circulating and distributing unit is divided into an air distributing compartment A, and air intake and fan compartment B, and a motor compartment C by the vertical partitions 33, 34 and 35.

The top of housing 32 is provided with an opening 36 which constitutes an air inlet opening into air intake compartment B. The lower end of the air duct 18 contained within the heater casing 16 is adapted to be connected to this air inlet opening 36, when the parts are arranged in the assembled relation shown in Figure 1. For this purpose the top wall of housing 32 may be provided with an upstanding sleeve 36a secured with in the opening 36 to telescopically receive the lower end of the air duct 18.

A fan 37 in the form of an axial intake radial discharge type of blower is disposed within the compartment B. The fan includes a casing having an intake opening 38 in the side thereof and an outlet opening 39 in a tubular extension 40. (See Figure 8). The partition 33, which separates the air intake compartment B from the air distributing compartment A, is provided with an opening just large enough to receive the tubular extension 40 of the casing forming a part of fan 37. Thus, the inlet opening 38 of the fan is disposed within air intake compartment B and the outlet opening 39 of the fan is disposed within the air distributing compartment A.

Fan 37 is driven by a motor 41 disposed in the motor compartment C (see Figure 6). The motor 41 is operatively connected to the wheel of fan 37 by a shaft 42 which projects through an opening in partition 34 provided for that purpose. Electrical current is supplied to motor 41 from a source, not shown, through electrical conductor 43. The motor 41 may be of the variable speed type so as to permit of regulation of the amount of heated air discharged by the fan.

The side walls 27 and 28 and the front wall 29 are provided with outlet openings 44, 45 and 46 for the discharge of air from the distributing compartment A. By providing discharge openings in three sides of the compartment, it will be recognized that air can be directed to any part of the room or space in which the apparatus is located. By locating the discharge openings at the floor level, heated air is discharged along the floor when the apparatus is used in the assembled relation shown in Figure 1.

The openings 44, 45 and 46 are provided with grill assemblies including vanes arranged to direct all of the discharged air downwardly and a part of the discharged air from each outlet in one direction and the remainder in another direction. The grills are all alike and so only the one installed in opening 44 will be described. It includes a plurality of vertically extending vanes 47 inclined in one direction and others 48 inclined in the opposite direction; and a series of horizontal vanes 49 all inclined downwardly.

In order to permit the distribution of heated air from outlets 44, 45 and 46 by conduits, if desired, the grills also include a tubular flange adapted to telescopically engage a suitable conduit.

Provision is made for regulating the proportion of air which is discharged from the distributing chamber A through each of the discharge openings 44, 45 and 46. This is accomplished by means of a pair of adjustable air guides 50 and 51 of a width approximately equal to the height of compartment A. (See Figure 6). Each of the guides

has one end pivotally connected to front wall 29 at opposite sides of the outlet opening 46. The opposite ends extend toward the discharge opening 39 in the tubular portion 40 of fan 37. By moving the free ends of guides 50 and 51 toward or away from each other and to the right or left (as viewed in Figure 6) the proportion of air discharged through each of the outlet openings 44, 45 and 46 may be varied and regulated as desired. It can all be discharged through one opening or it can be evenly distributed among the three or it can be varied at any desired place between these extremes, merely by adjusting the positions of guides 50 and 51.

From the description thus far given the operation of the apparatus shown in Figure 1 will be readily apparent. When the fan 37 is not in operation, it will be as follows: the heat produced by stove 11 will set up a gravity circulation of air so that cold air will be drawn into the casing 16 through the openings 17 and heated air will be discharged from the casing through openings 18.

When the fan 37 is in operation, cold air will continue to be drawn into the casing 16 through the openings 17. But the heated air will not be discharged through the openings 18. Instead it will be drawn into the upper end of air duct 18, from there into intake compartment B, then through fan 37 into distributing compartment A, and finally be discharged under pressure through outlet openings 44, 45 and 46. The size of duct 18 and the inlet opening 20 thereinto should and can be so proportioned that when the stove and fan are both working at maximum capacity, substantially all of the heated air is drawn into duct 18 and discharged from openings 44, 45 and 46 and substantially none of the heated air is discharged through openings 18. Care should be taken also to prevent drawing cold air into the apparatus through openings 18.

In some cases, such as trailers, for example, it is desired to introduce some fresh air into the circulating system in the winter and to circulate the cool outside air through the structure in the summer time. Provision is made in the present apparatus to accomplish both of these advantageous results.

Partition 35 which forms the back wall of air intake compartment B is provided with an opening 52 which constitutes a second air inlet opening into compartment B. (See Figures 8 and 9.) The rear wall 30 of the air circulating unit 25 is also provided with an opening 53 communicating with compartment C as well as with opening 52 in compartment B. Thus, air from the outside of the apparatus may be drawn directly into the air intake compartment B through the openings 53 and 52. The wall 30 surrounding opening 53 is preferably flanged as at 53a so that a conduit can be attached thereto, if desired. By the use of such a connection the opening 53 may be placed in direct communication with the air outside the structure in which the apparatus is located.

As motor 41 is in compartment C which is always open to the outside air through opening 53, the motor cannot become overheated by hot air from the stove.

In order to regulate the proportion of air admitted to air intake compartment B through openings 36 (heated air) and 53 (cold air), an adjustable damper 54 is provided. The damper is of a size to completely cover either of these openings. It is mounted upon a shaft 55 rotatably supported by the housing 32 and having a free end extending through the side wall of

housing 32. A handle 56 is secured to the free end of the shaft 55 exteriorly of the apparatus so as to permit convenient rotation of the shaft to adjust the position of the damper 54. Suitable provision is made to hold the damper in any desired position. In Figure 8, the damper is shown in position as a closure for opening 36 so that all air is admitted to compartment B through opening 53. In order to close opening 53 and opening 36, all that need be done is to rotate shaft 55 to its extreme counterclockwise position in Figure 8.

From the foregoing, it will be seen that the present invention provides a novel, compact and inexpensive arrangement of parts for providing a 15 circulating heater with a forced air circulation which is adapted to discharge heated air at the floor level, without interfering with the capacity of the heater to function as a gravity circulator.

The scope of the invention is indicated in the appended claims.

I claim:

1. A device of the character described comprising a plurality of upright walls forming an enclosure, a heater casing supported upon said walls, an upright partition in said enclosure dividing the same into an air intake chamber and an air distributing chamber and having an opening forming a passageway between said chambers, a generally horizontal wall supported by said upright walls between said enclosure and said heater casing, said horizontal wall having an air inlet opening forming a passageway between said heater casing and said intake chamber, said intake chamber having an air inlet opening in an 35 upright wall thereof communicating with the atmosphere exteriorly of said enclosure and casing, means for selectively closing one or the other of said inlet openings, said distributing chamber

having an outlet opening in the upright wall thereof, and a fan located in said passageway between said air intake chamber and said air distributing chamber and for withdrawing air from the intake chamber and discharging it into the distributing chamber.

5 10 15 20 25 30 35 40 45 50 55 60 65 70 75 80 85 90 95

2. A device of the character defined in claim 1 wherein said air distributing chamber is provided with openings in three upright sides thereof and means is provided in said distributing chamber for proportioning the quantity of air discharged from said three openings.
